UNITED STATES PATENT OFFICE.

AMBROSE A. HASTINGS, OF NEWARK, NEW JERSEY, ASSIGNOR OF ONE-TENTH TO WILLIAM DIXON, OF SAME PLACE.

LAMP.

SPECIFICATION forming part of Letters Patent No. 247,822, dated October 4, 1881.

Application filed February 21, 1881. (No model.)

To all whom it may concern:

Be it known that I, AMBROSE A. HASTINGS, of Newark, in the county of Essex and State of New Jersey, have invented a new Improvement 5 in Lamps, of which the following is a full, clear, and exact description.

Figure 1 is a sectional side elevation of my improvement. Fig. 2 is a sectional plan view of the same, taken through the line *xx*, Fig. 1. 10 Fig. 3 is a side elevation of a part of the same.

The object of this invention is to improve the light-giving qualities of lamps and secure greater safety in their use.

The invention consists in constructing the 15 oil-chamber and the globe of a lamp in one piece; also, in the combination, with the grooved neck of the lamp and with the burner-collar having flange, of the rubber packing-ring and the clamping-plate and its nut, whereby the 20 burner-collar will be securely connected with the lamp; also, in the combination, with the stationary part of the globe having recesses in the outer surface of its upper part, and the movable part of the globe having recesses in the 25 outer surface of its lower part, of the spring-button and its pivoting-screw, whereby the said stationary and movable parts of the globe are securely connected; and, also, in the combination, with the stationary part of the globe 30 and the clamping-plate, of the key and its bearing and spiral spring, whereby the wick can be adjusted without interfering with the removal of the burner, as will be hereinafter fully described.

35 A represents the oil-chamber of a lamp, the top opening of which is designed to be a little larger than the ordinary top opening of a lamp.

B is the lower part of the globe, which is made solid with the oil-chamber or body A of the lamp. The part B of the globe may be half 40 a globe, or more or less than half a globe, as may be desired.

In the lower part of the globe B are formed 45 openings C to admit air to support combustion. In the inner surface of the neck of the lamp is formed a half-round groove, D, to receive a packing-ring, E, of rubber or other suitable material.

F is the lamp-burner, which is screwed into 50 a collar, G, in the ordinary manner.

Upon the lower end of the collar G is formed a ring-flange, H, of such a size that it can be passed in and out through the neck of the lamp. The outer edge of the flange H is inclined, flared, or curved downward to fit against the 55 lower inner part of the packing-ring E.

I is a ring-plate that fits upon the collar G, and rests and fits upon the inner surface of the lower part of the globe B and upon the upper inner part of the packing-ring E. The ring-plate I is held down to its place by a nut or screw-collar, J, screwed upon the outer surface of the upper part of the collar G. With this construction, by screwing down the nut J the packing-ring E will be compressed between 65 the flange H and the plate I, and will be firmly forced into the groove D, so as to hold the burner-collar G securely, and allow the burner F to be screwed in and out, as required. The plate I is finely perforated over the openings 70 C, to allow the air to pass in freely.

In the outer surface of the upper part of the globe B are formed recesses K, to receive the coiled ends of the springs L, which are pivoted in the said recesses by screws M, formed up- 75 on or attached to the ends of the said springs, passing through the outer coils of the springs and through the globe B, and having nuts screwed upon their inner ends.

The outer or free ends of the springs L have 80 knobs or points formed upon or attached to them, to enter recesses N in the outer surface of the upper or detachable part, O, of the globe, and thus hold the said part O securely in place. The lower edge of the upper part, 85 O, of the globe overlaps the upper edge of the lower part, B, as shown in Fig. 1, so as to give the said part O a firm seat. The upper part, O, of the globe has an opening formed in its top for the escape of heated air and the gaseous products of combustion, which opening 90 may be surrounded by a flange or chimney, P, formed solid with the said part O.

Q is the stem that carries the spur-wheels that raise and lower the wick. The stem Q is 95 made short, and one or both of its ends are squared to fit into a similarly-shaped socket in the inner end of the key R, which passes through one of the holes C in the globe B, and through a bearing, S, formed upon or attached to the 100

plate I. The key R is pressed outward, and thus held out of contact with the stem Q, by a spiral spring, T, placed within the bearing S, that carries the said key. The key R has a button or other suitable handle attached to its outer end for convenience in operating it. With this construction the burner F can be readily screwed into and out of its collar. With this construction, also, when the lamp-wick is to be adjusted the key is pushed inward to cause its inner end to engage with the stem Q, so that the wick can be adjusted by turning the said key R.

A key, R, may be placed at each side of the globe B, so that the wick can be adjusted from either side of the lamp.

The oil-chamber A may be provided with a filling-aperture, U, or it may be filled through its neck by taking out the burner F.

Having thus described my invention, what I claim as new, and desire to secure by Letters Patent, is—

1. A lamp constructed, substantially as herein shown and described, with a globe, B, formed in one piece with the oil-chamber A, as set forth.

2. In a lamp, the combination, with the grooved neck of the lamp, and with the burner-collar G, having flange H, of the rubber packing-ring E, the clamping-plate I, and the nut J, substantially as herein shown and described, whereby the burner-collar will be securely connected with the lamp, as set forth.

3. In a lamp, the combination, with the stationary part B of the globe, having recesses K, and the separate part O, having recesses N, of the spring-buttons L and their pivoting-screws M, substantially as herein shown and described, whereby the separate part of the globe can be readily removed and will be securely held, as set forth.

4. In a lamp, the combination, with the stationary part B of the globe and the clamping-plate I, of the key R, the bearing S, and the spiral spring T, substantially as herein shown and described, whereby the wick can be adjusted without interfering with the removal of the burner, as set forth.

AMBROSE A. HASTINGS.
